UNITED STATES PATENT OFFICE.

BRONSON C. WOODFORD, OF DALLAS, TEXAS, ASSIGNEE TO THE MURRAY COMPANY, OF DALLAS, TEXAS, A CORPORATION OF TEXAS.

COTTON-PRESS-DOOR CONTROL.

Application filed January 24, 1928. Serial No. 249,026.

My invention is a counterbalance device for cotton press doors, designed to be attached permanently to each press box, and in the case of a double press, in which the 5 two bale boxes turn upon a central pivot, to travel with the box to which it is secured. Preferably each press box is provided with four of these devices, symmetrically disposed about the box—two devices controlling each 10 of the two side doors of the bale box.

In the drawings:

Figure 1 is a side view of a press box, to which my devices are attached;

Figure 2 is a partial front view of a box, 15 showing my device attached at one end of the door shaft;

Figure 3 is a view, in section, on an enlarged scale, of the sprocket sector, showing, by comparison with the dotted arc, the volute 20 form of the sector.

It has long been customary to provide counterbalance weights for press box doors, the weights being mounted in guide frames, with ropes running up above the press box, 25 over sheaves or pulleys and provided with hooks upon their free ends, to engage the press door on both sides, which hooks were engaged before the door was released to open and let down and disengaged after the 30 door had been closed again, before the box was rotated to set it in feeding position and bring the other press box into compressing position. This unhooking and hooking had to be performed at each change of position 35 of the box, the weights having to be lifted and lowered each time to accomplish this and the door manually controlled against the unvarying urge of the weights.

In my device the door control is permanently associated with the door which it 40 controls, travelling with it, is substantially automatic and is designed so as to compensate for the varying leverage exerted by the door in its opening and closing action 45 and to cause it to open and close steadily and evenly with almost no labor on the part of the operator.

In the drawings, A is the press box, B the press door, C the platform and D the 50 pivot to which the press boxes are secured and about which the boxes and platform turn, all as is usual. The door B is secured upon a shaft 1, by brackets 1^a, the shaft being mounted for turning in bearings 2, 55 secured to the sides of the press box. The

shaft 1 projects beyond one or both of the bearings to receive hub, 3, of an arm 4, which carries at its free end a sector 5 having preferably teeth 5^a.

The arm 5 lies in line, substantially, with 60 the brackets 1^a and the door B as shown at the left of Figure 1 and when the door is lowered to the position shown at the right of Figure 1, the arm is turned 90 degrees more or less. To one end of the sector 5 is 65 pinned at 52 a flexible connector, preferably a chain 6, the links of which cooperate with the teeth 51 of the sector 5. The other end of the chain 6 is connected to one end of a helical spring 7, shown in the drawings as a 70 tension spring, and the spring 7 is connected at the other end to a bracket 71 fast to the press box A, with provision, by means of a nut and threaded connector, 72, to adjust the tension and resistance of the spring 7. 75 The press doors A are provided with customary means to hold them in closed position, in the drawings shown as links, a, one end of which is anchored upon one door and the other end of which carries a loop a' 80 which may be passed over a stud a² upon the other door, as indicated in dotted lines in Figure 1.

The sector 5 is preferably not a segment of a circle struck from the centre of the hub 85 but is volute in form, the end to which the chain 6 is pinned being nearer to the hub centre than the opposite, or free end. The effect of this is to set the links of chain 6 firmly upon the teeth 51 of sector 5, as the 90 sector turns, and shift the point of engagement and strain to the several sector teeth successively, as the sector turns, and relieve the pin engagement 52 of strain and at the same time to progressively increase the 95 leverage in favor of the spring 7, increasing its effect.

The operation is as follows: The bale having been compressed, the links a, a', are disengaged, leaving the door or doors free to 100 open. The spring 7 being connected to the inner ends of the sector 5 (see Fig. 1) tends, at this time, to hold the doors closed, the doors being vertical and having little tendency to fall outwardly, except for the slight 105 motion due to some lateral expansion of the compressed bale released from the resistance of the doors. The operator now pulls the door outwardly, the sector 5 turning and winding up the chain 6, thus putting the 110

spring 7 under progressively increasing tension, the tension regularly increasing as the door swings down and regularly increases its leverage, to compensate for the increased leverage of the door and continuously balance the door. The spring being helically wound increases its resistance in exact proportion with its elongation, so that, at the point of greatest leverage of the door, when it is fully opened, the spring is giving its greatest resistance and so at all points between, the spring balances the urge of gravity acting on the door, a substantially perfect balance being maintained at all times, the spring either being designed or adjusted, by means of the nut and connector 72, to this end. When the bale has been removed the door is swung up, the operation being reversed, the spring growing progressively less urgent as the door approaches its vertical or closed position, but, due to the small leverage provided by the inwardly projecting end of the sector, to which the chain 6 is pinioned, the spring will completely close the door and hold it closed during the time that the links, α , α' , are being adjusted. The press is now ready to be revolved, bringing a filled bale box into position for compression, when the operation is repeated.

30 I have described and shown the sector as provided with teeth to cooperate with the links of a chain, and this is the preferred

construction, but I do not limit myself to this construction as a smooth groove sector and a cable or any flexible connector, would 35 be effective, in place of the toothed sector and cooperating chain.

I claim:

1. In a baling press, a press box door fast to a shaft extending across the box; 40 that shaft, mounted in bearings at either end of a box and projecting beyond a bearing; those bearings; a hub, carrying a grooved sector, secured upon the end of the shaft; a flexible connector pinned at one end to one end of the sector and at the other end 45 engaging one end of a helical spring; that spring, its other end secured to an abutment upon the bale box.

2. In a baling press, a press box door fast 50 to a shaft extending across the box; that shaft, mounted in bearings at either end of the box and projecting beyond a bearing; those bearings; a hub, carrying a volute toothed sector, secured upon the end of the 55 shaft; a chain pinned at one end to one end of the sector and at the other end engaging one end of a helical spring; that spring, its other end secured to an abutment upon the bale box.

Signed at Dallas, Texas, this 17th day of January, 1928.

BRONSON C. WOODFORD.
